United States Patent Office

Des. 185,765
Patented July 28, 1959

185,765

FOOD AND DRINK MIXER

Alfred W. Madl, Milwaukee, Wis., assignor to The John Oster Manufacturing Co., Milwaukee, Wis., a corporation of Wisconsin

Application February 13, 1959, Serial No. 54,598

Term of patent 14 years

(Cl. D44—1)

Fig. 1.

Des. 185,765

PAGE 2

Figure 1 is a front perspective view of a food and drink mixer embodying my new design;

Figure 2 is a front elevational view;

Figure 3 is a side elevational view;

Figure 4 is a cross sectional view taken on the line 4-4 in Figure 2; and

Figure 5 is a cross sectional view taken on the line 5-5 in Figure 2.

The dominant features of my design reside in those portions thereof shown in full lines.

I claim:

The ornamental design for a food and drink mixer, as shown and described.
